UNITED STATES PATENT OFFICE.

ERNEST YEOMAN ROBINSON, OF WITHTINGTON, MANCHESTER, ENGLAND, ASSIGNOR
TO ASSOCIATED ELECTRICAL INDUSTRIES LIMITED, A BRITISH COMPANY.

VACUUM ELECTRIC TUBE DEVICE.

Application filed November 26, 1924, Serial No. 752,480, and in Great Britain December 18, 1923.

This invention relates to vacuum electric tube devices and provides an improved construction and mounting of the electrodes of such devices. The invention more especially but not exclusively concerns the electrodes of such tubes wherein the inter-electrode gap is small, the object being a construction in which the electrodes are registered and maintained registered or accurately and rigidly disposed with respect to one another.

In vacuum electric tubes as heretofore commonly constructed wherein the electrodes are of tubular formation, the grid 15 comprises a number of turns of wire and is welded, lashed or otherwise attached along its length to a supporting stem. For example the stem may consist of a wire which is bent so as to have two parallel and adjacent arms between which the convolutions of a helical grid are clamped.

In such a construction, although individual turns or convolutions of the grid helix are self-supporting in themselves, the whole 25 helix is not self-supporting, but is flexible. With such a construction it is not possible to register the grid helix or convolutions accurately with regard to the grid support, to which they are welded or lashed, and the 30 grid is therefore unsuitable for use in a valve wherein the inter-electrode gap is small because of the lack of registering means. In such known constructions welding is the only method by which the grid 35 helix may be secured to the support in accurate and predetermined relation thereto. However, with such constructions even when the grid helix is secured to the support by welding accurate registration thereto can- 40 not be obtained when the grid wire is fine. This is because if the grid wire is of nickel or the like, it is distorted during welding and moreover each individual turn of the 45 grid helix is not sufficiently strong to prevent movement due to handling or to its own weight when it is heated in the valve. On the other hand, if the grid is of tungsten, for example, which material is very stiff at 50 room temperature and is still strong at high temperatures it is not possible to weld it easily to a support without distortion and even when it is so welded the weld is not sufficiently strong to act both as a means for securing the helix to the support and to 55 register the helix to the support. In other

forms of tubes the grid electrodes have been constructed of metal frames having grid wire wound thereon, but in such case the individual turns of the grid are not self-supporting and the grid wires are in effect suspended across the metal supporting frame.

According to the present invention a tubular grid of wire in coil, mesh or other open-work formation is secured to a rigid support which presents at least two lines of contact to the turns or meshes of the wire grid proper substantially throughout the length of the latter. In this manner a wire grid which is necessarily of a flexible nature is rendered comparatively rigid and can be 60 readily constrained or registered to occupy a predetermined position with respect to other electrodes since the wire grid is definitely and accurately registered with respect to the grid support, which in turn can be 65 constrained or registered with respect to the other electrodes in a suitable manner. Thus the grid may be accurately and positively located in the small gap between a 70 filamentary cathode and a tubular anode 75 closely spaced therefrom.

The grid wire may be secured to the support in various ways such as by welding or lashing. In the case where the support presents more than two lines of contact to 80 the grid proper separate means for securing the wire grid tube thereto may be dispensed with if it is arranged that at least three lines of contact are formed which are so spaced around the grid tube that the latter is held thereby but even in this case additional securing means may be used, at 85 the ends of the grid tube for example. As pointed out above the grid is accurately registered with respect to the support and may 90 be mounted in position with reference to the other electrodes by means of the support. However, the grid itself when it consists of tungsten is so rigid and strong that 95 it may be held in a jig with the other electrodes and positioned therein by a wire or tube passing down the grid helix while the electrode supports of the valves are pinched into glass serving as a spacing medium.

The supports are conveniently in the form 100 of V-blocks which are of substantially the same length as the wire grid tube, or in some cases slightly longer to provide registering portions.

The form of the support and the mount- 110

ing thereof may vary with the nature and form of the other electrodes of the vacuum tube. To enable the invention to be clearly understood several arrangements will now be described by way of example with reference to the accompanying drawings in which,

Fig. 1 is a perspective view of a simple form of the improved grid in accordance with the invention, and Fig. 2 an end view thereof. Figs. 3 and 4 are sections of modified forms of the support for the grid helix. Figs. 5 and 6 are respectively a plan view and a transverse section of another form of grid in accordance with the invention. Figs. 7 and 8 are detail views of a grid structure suitable for a valve having a twin filament, and Fig. 9 is a perspective view of the complete grid structure. Figs. 10 and 11 are respectively a front elevation, and a side elevation partly in section, of an electrode structure of a valve including a grid in accordance with the invention.

Referring to Figs. 1 and 2 of the drawings, the grid therein illustrated comprises a wire helix 1 of tungsten, molybdenum or nickel for example, tungsten being preferred since by the use of this material a rigid grid is obtained and in the case of power valves the helix is better able to withstand the high temperature which it acquires when located in close proximity to the cathode.

The wire helix 1 is mounted upon a grid support 2 which comprises a flat slab or bar of metal, for example molybdenum, having along one edge thereof a V-groove 3. The grid helix 1 rests in the groove or against the two outer edges created by the provision of the groove 3 and is secured in position by means of binding wire 4 passing between the convolutions of the helix and around the slab or bar 2. Instead of a V-groove the slab or bar 2 may be provided with a groove of circular section the radius of which is substantially equal to or is slightly less than the radius of the grid helix 1. The bar 2 has a thickness of at least one-twelfth the periphery of the helix 1, as will be seen from the drawing, to insure rigidity of support of the helix. Instead of employing a solid slab or bar 2 a grid support may be employed comprising for example two strips 5 and 6 of sheet metal suitably secured together such as by stapling, welding or riveting, and having each a splayed-out edge 7 by which the groove 3 is constituted. Or as shown in Fig. 4 the support may consist of a sheet or strip 8 of metal folded at 9 around a rod 10 which may constitute a supporting stem for the grid structure, the edges being splayed out providing the groove 3 as described in connection with Fig. 3.

Grids constructed as above described may be supported within the valve envelope by means of stems or wires welded to the grid support or integral therewith and them-

selves pinched within the foot or seal of the valve. Or as mentioned in connection with Fig. 4 the wire or rod 10 may constitute the grid support.

As previously herein set forth the grid support may present more than two lines of contact to the grid wire and Figs. 5 to 9 inclusive illustrate examples of this kind. In Figs. 5 and 6 the grid helix 1 is shown supported between a pair of grooved slabs 2 located in a common plane and having the grooved edges directed towards one another and partially embracing the helix 1. The slabs may be connected together by means of cross strips 14 arched as 15 so as to embrace the ends of the grid helix 1 and secured to the slabs 2 by welding or otherwise. Instead of the slabs 2, built-up supports such as illustrated in Figs. 3 and 4 may be employed. Thus in Figs. 7, 8 and 9 two grid helices 1 of tungsten or molybdenum for example are carried in a support comprising two metal plates 16 of molybdenum stamped or pressed to the form clearly shown in Fig. 9, that is to say provided with a plurality of windows 17 and integral arched connecting strips 18. The edges of the cut-out window portions are splayed as indicated at 19 to provide the V-grooves hereinbefore referred to. The plates 18 may be fastened together by means of staples as indicated at 20 or they may be welded, riveted or otherwise secured together.

A tubular grid of the kind illustrated in Figs. 1 and 2 may be supported along with the other electrodes of the tube in the following manner.

Referring to the construction illustrated in Figs. 10 and 11, the grid is of the type illustrated in Figs. 1 and 2 except that the support 2 is provided with slots 39 by means of which the grid is registered in position with reference to the other electrodes which are mounted upon a framework which is generally of similar general construction to that illustrated and described in my copending application Serial No. 722,811 filed June 27, 1924. There are two such grids which co-operate with two anodes 40, each anode being preferably formed of molybdenum sheet. The filaments are supported and registered in the manner described in the specification of my copending application, Serial No. 717,327, filed 2nd June, 1924. At their lead-in ends the filaments are supported by means of supports 44. The two filaments are in a plane at right angles to that containing the insulating side members 26 of the framework. The upper end of the filament is constructed in the manner described in the specification of my copending application, Serial No. 745,194, filed Oct. 22, 1924, the short-circuiting strip 45 comprising a

molybdenum strip so shaped as to be flexible in the axial direction of the filament, as described in the specification just above mentioned. The filament wires pass through 5 a constraining strip 46 which is provided with end perforations through which the side members of the framework pass and small perforations through which the filaments pass and are thereby registered whilst 10 held in tension by means of springs 49 which engage nickel tabs 50 attached to the upper ends of the filaments. The springs 49 are in turn secured to angle brackets of nickel 15 51 welded or otherwise attached to the upper frame member. The registering cross piece 46 is held in spaced relationship from the end member 27 of the framework by means of two nickel wires 52 welded respectively to the frame member and to the 20 cross piece 46. The two grids are supported on the framework by means of two cross pieces 53, each of which comprises a metal plate having end perforations for the side members of the framework and other perforations adapted to receive the respective 25 ends of the grid supports 2 and having portions adapted to be engaged within the slots 39 within the ends of the grid supports 2, thereby registering and holding the grids 30 in position upon the framework.

The two anodes are supported from the framework by two cross pieces 58, each of which comprises a metal plate having end perforations to permit it to be mounted on 35 the side members of the framework and having two inwardly extending slots of shape corresponding to the external contour of the anode members 40. The various cross pieces may be secured upon the vitreous side members of the framework by binding 40 with wire. The valve described in connection with Figs. 10 and 11 is of the type set forth in the specification of my copending application, Serial No. 603,715, filed 45 27th November, 1922, aforesaid. The inter-electrode space is small and the discharge at the ends of the filaments is confined to the inter-electrode space by reason of the fact that the ends of the filament are cooled. 50 Discharge through the open portions of the anodes along the length of the filaments

is prevented by reason of the presence of the grid supports 2 which being comparatively thick exert both an electrostatic and a mechanical screening effect upon the discharge. The anode lead-in wire 63 is connected to the two anode cross pieces 58 whilst the lead-in wire 64 for the grid is connected to the two grid cross pieces 53. 55

It will be understood that various modifications may be made without departing from the scope of the invention.

I claim as my invention:—

1. For a vacuum electric tube, a grid structure comprising an openwork tube 65 formed of wire, a bar having a channel edge which receives and partially embraces the exterior of said tube grid, and means for firmly holding said tube grid in engagement in said channel edge. 70

2. For a vacuum electric tube, a grid structure comprising an openwork tube formed of wire, a supporting member therefor in the form of a bar consisting of two thicknesses of sheet metal splayed out along 75 one edge to form a channel, and means whereby said tube grid is held in firm engagement in said channel.

3. For a vacuum electric tube, a grid structure comprising an openwork tube 80 formed of wire, a supporting member therefor in the form of a bar consisting of a strip of metal folded symmetrically about itself, a supporting rod enclosed in the fold of said folded strip, the free edges of the folded 85 strip being splayed out to form a channel, and means whereby said tube grid is held in firm engagement in said channel.

4. For a vacuum electric tube, a grid structure comprising an openwork tube 90 formed of wire, a bar having a thickness of at least one twelfth the periphery of said tube grid and formed with a channel edge which engages along the exterior of the tube grid, and means for firmly holding the exterior of said tube grid in engagement in said channel edge. 95

In testimony whereof I have hereunto subscribed my name this 15th day of October, 1924. 100

ERNEST YEOMAN ROBINSON.
